UNITED STATES PATENT OFFICE.

JAMES S. CUSHMAN, OF NEW YORK, N. Y.

DEVICE FOR DISPLAYING CARDS, PRICE-TICKETS, &c.

SPECIFICATION forming part of Letters Patent No. 716,389, dated December 23, 1902.

Application filed October 13, 1900. Serial No. 32,925. (No model.)

To all whom it may concern:

Be it known that I, JAMES S. CUSHMAN, a citizen of the United States, residing in the city, county, and State of New York, have invented a certain new Improved Device for Displaying Cards, Price-Tickets, &c., of which the following is a specification.

The object of my invention is to provide a cheap, useful, and effective device for displaying, for instance, price-cards in show-windows and for other analogous purposes. To this end I form the device of a single piece of wire having a flat base, upon which it stands, composed of convolutions of wire, preferably of approximately circular or of convolute formation, from the center of which rises a portion composed of parallel sections of the wire so disposed as to form a clip or clamp, within which the card, price-ticket, or other article may be received and held.

Of course the bends and convolutions of the wire may be greatly varied in a device of this kind and yet retain the characteristics or adaptation to the uses above suggested.

The accompanying drawing is a perspective view showing a device of practical and effective form capable of being manufactured most economically.

Starting with one end of the wire *a*, it is carried around, preferably, in two or more and by preference in three approximately circular convolutions *b c d* of decreasing diameter. Preferably at or about the center of this formation the wire rises vertically, as at *e*, then extends downwardly, as at *f*, then upwardly, as at *g*, inside of *e*, and then downwardly, as at *h*, inside of *f*, these portions of the wire preferably being in the same plane. The device constructed in this manner or in substantially the same or an equivalent manner has a flat base *b c d*, upon which it stands, and a vertical centrally-disposed clip. A card or similar article may be held in this clip by forcing its edge downwardly between *e* and *f* and *g* and *h*. When it is desired to use this

device to hold price or other cards upon books or magazines, the outer convolution *b* of the base may be slipped under the cover or within the leaves of the book, while the next convolution *c* may pass outside of the cover, the 50 base part of the device being then clamped to the book.

I do not limit myself to the special conformation of the device illustrated and described, but claim, broadly, such a device 55 made from a single piece of wire bent to form a supporting-base and an upright card-retaining clip.

I claim as my invention—

1. The herein-described card or price-ticket 60 holder, formed from a single continuous piece of wire bent to form a coil constituting an extended self-supporting base, and a vertical card-retaining clip formed by coils of wire arranged in the same vertical plane, and disposed centrally with reference to the base.

2. The herein-described card or price-ticket holder made from a single continuous piece of wire bent to form a flat, self-supporting base having a plurality of convolutions of 7c wire arranged in the same horizontal plane, and an upright card-retaining clip made from coils of the wire arranged in the same vertical plane.

3. The herein-described card or price-ticket 75 holder formed from a single continuous piece of wire wound in convolutions of decreasing diameter in the same horizontal plane to form a flat, self-supporting base, and then extending upwardly centrally from said base, then 80 downwardly, then upwardly, and downwardly again in the same vertical plane to form a card-retaining clip.

In testimony whereof I have hereunto subscribed my name.

JAMES S. CUSHMAN.
